UNITED STATES PATENT OFFICE.

ALBERT K. MANSFIELD, OF NEW YORK, N. Y.

RAILROAD-SWITCH AND SWITCH MECHANISM.

SPECIFICATION forming part of Letters Patent No. 391,168, dated October 16, 1888.

Application filed March 6, 1888. Serial No. 266,384. (No model.)

To all whom it may concern:

Be it known that I, ALBERT K. MANSFIELD, a citizen of the United States, residing at New York, in the county of New York and State of New York, have invented a new and useful Improvement in Railroad-Switches and Switch Mechanism, of which the following is a specification.

My invention relates to railroad-switches and mechanism for operating the same; and the objects of my improvement are to render split switches more safe against derailment of trains approaching their facing-points, and to so construct their operating mechanism that trains may safely trail through the switch when it is closed against them and leave the switch set as they found it or otherwise, as may be desired. I accomplish these objects by the mechanism illustrated in the accompanying drawings, in which—

Figure 1 is a plan view of a portion of a split switch with guard-rails and operating mechanism complete. Fig. 2 is a vertical cross-section through center of switch-stand. Fig. 3 is a sectional plan on line A of Fig. 2. Fig. 4 is a partial end view of stand and lever. Fig. 5 is a partial elevation of lever-yoke. Fig. 6 is an elevation of latch-stand. Fig. 7 is an end elevation of guard crank-arm. Fig. 8 is a diagram showing plan of one switch-point in contact with its main rail, and Fig. 9 is another diagram showing a plan of the other switch-point in contact with its main rail.

9 is a main rail on turn-out side of track, which is bent sharply at 10.

11 is the main rail lying entirely in the main track, and is bent sharply at 12, 13, and 14.

15 16 are guard-rails to protect the switch-points. They are arranged to turn about their heels 17 17, are connected together by the rods 18 19, and both connected to the switch-stand by the connecting-rod 20.

21 22 are the switch-rails, which are held fast in the usual way at their heels, (not shown,) and which are connected together by the rods 23 24. These switch-rails are shaped in the usual manner, except that instead of the faces of their heads which lie toward the center of track being made in one straight line they are cut off at an acute angle with this face near their points, as shown by line 25 26 in Fig. 8. The switch is then placed so far from the bend

10 of main rail that a wave is formed in the track or a triangular cut taken out, which is represented by the triangle 10 25 26, the line 55 10 26 being in the same straight line as the switch-rail back of point 26 and as face of main rail before point 10. The height of this triangle to point 25 is such that any small obstruction back of the switch which prevents 60 its being thrown way home may not force the point out beyond the line 10 26 or the gage-line of track. Moreover, when the switch is thus obstructed, or for any reason is not entirely home, wheels running close to the rail 65 will act against the line 25 26 of the wedge-shaped point, tending to force the switch 70 home. Thus the switch is much safer than if its point extends up to or near to the bend 10. In order to gain the same safety on the other 75 rail of the track, the triangle 12 13 14 is formed, the side 12 13 corresponding to the side 10 25 of the other rail, and the side 13 14 being the part of the main rail against which the switch fits.

27 28 are top and bottom parts of the main casing of the switch-stand. This casing has journal-bearings 29 30 for the vertical shaft 31, also journal-bearings for the bevel-pinnions 32 33.

34 is a bevel-segment made fast to shaft 31 and carrying a crank-arm, 35, to which is attached the spring-rod 36, bearing the spring 37, which abuts against a part of the casing. The gear 34 meshes with 32 and 33. Attached 80 to and forming a part of 34 is the crank-arm 38, to which is pivoted the connecting rod 39, which connects stand to switch. The arm 38 is of such length that the shaft 31 ordinarily turns through one-fourth of a revolution in 90 throwing the switch. The shaft 31 may carry or be arranged to operate any desired form of signal. The stud which carries pinion 33 bears at its other end a short crank-arm, 40, to which is pivoted one end of the connecting- 95 rod 20.

The relation of gear 33 to 34 is such that in throwing the switch 33, and therefore the crank 40, turns through more than one-half a circle. The crank is also so placed that the movement 100 of the guard-rails 15 16 caused by it is in opposite directions to the movement of the switch. This enables the adjustments to be so made that each guard-rail in turn guards its oppo-

site switch-rail. Moreover, wheels which press against the guard-rail which is in action, or nearest the main rail, tend to press the switch more firmly home; for, since the end of connecting-rod 20 is thrown past the dead-center in moving the guard-rail to position, any pressure against this rail tends to throw the crank 40 farther past the dead-center, and therefore tends to force the switch farther in 10 the direction in which it last moved—that is, toward home. The relation of pinion 32 to gear 34 is such that 32 is turned through about one-half a revolution.

Strictly speaking, two bevel-gears of 15 equal size, like 32 and 33, cannot work correctly in the manner shown with the same bevel-gear 34; but a slight variation in the regular method of shaping the teeth of one or more of the gears overcomes all difficulty. The 20 pinion 32 is preferably made in one piece with its stud, which passes through and beyond its journal-bearing, and receives the pivoted hand-lever 41 on its free end. The lever is pivoted to the gear at 42, as shown. This 25 method of attaching the lever to the pinion enables the former to, when not in use, be thrown around in line with the axis of the pinion, and there, by suitable arrangement, locked to place. A lug or guard, 43, is formed 30 outside the pinion-journal, of such form that if the lever has not been thrown to a horizontal position its projecting end 44 will, by coming in contact with the lug 43, prevent the lever being thrown to position to be locked; but if 35 the lever has reached a horizontal position the end 44 will swing freely past the lug. A yoke or guard, 45, is, moreover, fastened to the ties on which the switch-stand rests, and is so formed that the lever must swing under it to 40 reach the position where it may be locked, but cannot be so swung unless it (the lever) has first reached its horizontal position. The function of the lug 43 and that of the yoke 45 are the same, and of course either may be dispensed with when the other is used; or other 45 special devices may be applied to accomplish the same purpose, all or any of which may be comprehended under the word "guard."

46 is a locking-stand having the hinged 50 staple 47 and the tongue 48, and which is so arranged that the lever may, if preferred, be locked in its first horizontal position instead of being turned around into the axis of the pinion.

55 Fig. 1, is a spring-pocket attached to switch-rod 23 and containing the spring 50. Passing through the spring is the connecting-rod 39. The spring is so arranged that when the switch is in one of its home positions 60 it is held there through the elastic force of the spring. When, however, the switch is in its other position, it is held positively home and the spring 50 is inoperative.

The application of spring to shaft 31 through 65 the spring-crank 35 is such that there is no definite home-point for the crank—in other

words, the movement is not completed until the switch is home against its main rail. Various other spring mechanisms may be adapted to contain this feature; but it is thought not to 70 have been used before.

Spring-operating switch-stands are generally so arranged that the spring ceases to act when the vertical shaft has completed its quarter-revolution.

75

In cases where the guard-rail mechanism is not used another crank, 35, and spring may be used, acting in an opposite direction to those shown, as indicated in dotted line in Fig. 3.

The connection between the switch and stand may be made as shown in full lines, or may be a rigid connection without spring, as shown by dotted lines in Fig. 1. In the latter case, and if the lever 41 is locked in line with pinion-axis, the switch-stand is completely 80 automatic—that is, if a train trails through the switch which is closed against it, either from main track or siding, the switch will be thrown by the first wheels of the train. Let it be understood that the spring within the 85 switch-stand is strong enough to prevent possibility of throwing the switch by hand without unlocking the lever, but that it is not so strong as to prevent the train from throwing the switch with ease. If now the spring-con- 90 nection be used between switch and stand, as shown, and if the operating-lever be locked by the locking-stand 46 when the switch is set for main track, and if the lever be left free in the position shown in dotted lines, Fig. 1, 95 when set for siding, then the switch-stand is automatic one way and the switch is automatic the other way. In other words, if a train runs out of the siding through the closed switch and locked stand, the switch will automatically 100 permit this and will be left closed after the train has passed, whereas if a main-track train trails through the open switch the train will immediately close the switch and it will 105 be left closed.

110

What I claim as my invention is—

1. The bend 12 13 14 in the continuous main rail of a track, in combination with split-switch point 22, substantially as and for the purpose set forth.

115

2. In combination, a movable split switch consisting of a pair of movable points connected together, a movable guard the general direction of whose movements is in opposite directions to those of the switch to protect said points, and a switch-stand connected to both switch and guard and having a hand-lever and connecting mechanism by which both switch and guard are operated directly from the stand by the same hand movement and by which the guard is locked in position to prevent movement through the action of wheel-flanges against it, substantially as described.

120

3. The combination of split switch 21 22, guard 15 16, switch-crank 38, having a movement of less than a half-circle, guard-crank 40, having a movement of more than half a circle,

130

hand-lever 41, having a movement of about a half-circle, and connecting mechanism, substantially as set forth.

4. In an automatic switch-stand, the combination of crank-arm 35, turning through about 5 ninety degrees, spring-rod 36, pivoted to said crank-arm, spring 37, abutting against a stationary part of the stand, and supporting parts, substantially as set forth.

10 5. The stationary lug 43, in combination with projecting end 44 of lever 41, when arranged as and for the purpose specified.

6. The pivoted operating-lever 41, which is 15 pivoted to the part on which it acts, so that it may be thrown into a position of no leverage, in combination with a suitable guard arranged to prevent the operating-lever from being thrown to its dead position unless it has first completed its operating movement, substantially as set forth.

7. In combination with split switch, automatic switch-stand, and locking device which holds the stand from operating when siding is closed, the spring-connection 49 50, which is 25 so arranged as to be flexible for trains trailing through switch from siding when the stand is locked against operating by said locking device, but is rigid or inactive for trains trailing through on main line, when the stand is free, by 30 reason of its automatic construction to be operated by the train, substantially as described.

8. In combination, a split switch which is automatic to trains running through it from one track, while it is non-automatic to trains running through it from the other track, and a 35 switch-stand which is automatic in the latter case, but non-automatic in the former, and connecting parts, substantially as set forth.

9. In an automatic switch-stand, the operating-lever 41, so pivoted to the part on which 40 it operates that it may be thrown out of operative position, in combination with locking-stand 46, so placed that in one position the switch may be locked, whereby the stand may be used as automatic both ways, or one way, as 45 may be desired, substantially as set forth.

10. In combination with a split switch, an automatic stand having a spring device to force and hold the switch home when arranged so that the extent of movement of said spring device is not limited by the construction of the stand, but is only limited by the positions of the track-rails, against which the switch-rails are forced by the spring, substantially as and 50 for the purpose specified.

55 In testimony whereof I hereunto subscribe my name.

ALBERT K. MANSFIELD.
